Primary Examiner — Llorellys Martinez*Assistant Examiner* — Kwabena A. Ankobiah(74) *Attorney, Agent, or Firm* — Birch, Stewart, Kolasch & Birch, LLP(57) **CLAIM**

We claim the ornamental design for a remote control for motion bed, as shown and described.

DESCRIPTION

FIG. 1 is a perspective view of a remote control for motion bed showing the new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings represent portions of the remote control for motion bed that form no part of the claimed design.
